FREDERICK N. PURDUE, OF EAST ORANGE, NEW JERSEY.

CUTTING DEVICE.

1,200,981.

Specification of Letters Patent. Patented Oct. 10, 1916.

Application filed November 2, 1915. Serial No. 59,253.

To all whom it may concern:

Be it known that I, FREDERICK N. PURDUE, a citizen of the United States, and a resident of East Orange, in the county of Essex and State of New Jersey, have invented a new and Improved Cutting Device, of which the following is a full, clear, and exact description.

The invention relates to shoe machinery, and its object is to provide a new and improved cutting or trimming device, more especially designed for cutting a temporary cover of linen or other fabric material close to the sole of a shoe, boot or slipper and without danger of cutting or marring the upper or sole of the shoe, boot or slipper.

In order to produce the desired result use is made of a knife having a cutting edge at one end and a sheath having a tapering open end through which extends the cutting edge of the knife, the said tapering end of the sheath protecting the surrounding parts of the shoe from being cut into by the said cutting edge.

A practical embodiment of the invention is represented in the accompanying drawings forming a part of this specification, in which similar characters of reference indicate corresponding parts in all the views.

Figure 1 is a sectional side elevation of the cutting device as applied, the parts being shown in elevation; Fig. 2 is a front end elevation of the same; and Fig. 3 is a similar view of a modified form of the cutting device.

In the manufacture of boots, shoes and slippers of colored leather or other material, it is the practice to cover the article with a cover of linen, cotton or similar fabric material, the cover being lasted in with the upper and sewn in afterward with the welt. After the shoe or slipper is finished the cover is cut as close as possible to the welt, and this operation is at present generally accomplished by hand. By the use of the cutting devices presently to be described in detail the expensive hand labor is dispensed with and the work is done more rapidly and with less danger of damage to the sole or upper of the shoe, boot or slipper.

The cutting device, as illustrated in Figs. 1 and 2, is mounted on a suitably constructed stand 10 provided at its upper end with a bearing 11 for a shaft 12 carrying a pulley 13 connected by belt 14 with other machinery for imparting a rotary motion to the shaft

12. The forward end of the shaft 12 is provided with an eccentric 15 on which is mounted a hub 16 of a sheath 17 through which extends a thin flat shaft 18 disposed at a right angle to the axis of the shaft 12. A cutting edge 19 is formed on the lower end of the shaft 18 and this cutting edge 19 projects through the open tapering lower end 20 of the sheath 17. The knife 18 is provided near its upper end with an adjustable collar 21 adapted to rest on the top of the hub 16. A spring 22 is connected at one end with the upper end of the knife 18 and at its lower end it is attached to the hub 16 to hold the knife 18 normally in lowermost position and to allow the knife to yield in an upward direction. It is understood that by having the adjustable collar 21, the cutting edge 19 can be adjusted so as to project but slightly beyond the open tapering end 20 of the sheath 17. It will also be noticed that the knife 18 can yield in an upward direction owing to the action of the spring 22. The hub 16 is provided with a set screw 23 projecting into an annular groove 24 formed on the eccentric end 15 of the shaft 12 to hold the hub 16 against axial movement on the eccentric 15.

The sheath 17 immediately below the hub 16 extends into a guide 25 provided with a pin 26 mounted to turn in the stand 10 to allow the guide 25 to oscillate in case an oscillating motion is given to the hub 16. The shoe, boot, slipper or similar footwear is provided with a cover 31 of linen, cotton or a similar fabric material, and sewed in with the welt. This cover 31 is to be cut by the cutting edge 19 of the knife 18 close to the sole 32 and for this purpose the edge of the sole 32 is adapted to be supported on an angular support 33 on the free end of an arm 34 pivoted at 35 on a link 36 fulcrumed at 37 on the stand 10. The spring 38 is interposed between the link 36 and the stand 10 to allow the link 36 to yield in a rearward direction.

In using the cutting device, the operator having hold of the work engages the edge of the sole 32 with the supports 33 and moves the work along as the cutting progresses so that the entire cover 31 is trimmed or cut off in close proximity to the welt. As described, the rotation of the shaft 12 causes an oscillation of the sheath 17 carrying the knife 18 whereby an oscillating motion is given to the knife 18 to cause its edge

19 to cut the cover 31. If desired, the shaft 12 may be stopped or held stationary and a vertical reciprocating movement may be given to the knife 18 by connecting the upper end of the said knife by a pitman 41 with suitable machinery for imparting an up and down sliding movement to the knife 18. If desired, a rocking movement may be given to the sheath 17 while the knife 18 is held stationary therein, the shaft 12 is at a standstill and the guide 25 is removed. For this purpose use may be made of a link 42 extending horizontally and connecting the upper end of the knife 18 with a suitable device for imparting a rocking motion to the sheath 17, the hub 16 of which is mounted to turn on an eccentric 15. If desired, the knife 18 may be fastened positively in place in the sheath 17 by the use of a set screw 50 in case a rocking movement is given to the sheath in either of the two forms above mentioned, but when a reciprocating up and down movement is given to the knife 18 by the link connection 41 then the set screw 50 is retracted to allow such up and down movement of the knife.

It is expressly understood that I do not limit myself to the particular movement given to the knife, that is, whether an up and down or oscillating movement is produced, it being, however, understood that in either case the movement giving to the cutting edge is very slight, say about one-sixteenth of an inch.

35 By providing the tapering end 20 of the sheath 17 a guard is provided for protecting the upper and the sole against being cut into or otherwise injured by the cutting edge 19 of the knife 18 especially as the cutting edge 19 is in close proximity to the tapering end 20 of the sheath 17 carrying the knife 18.

Having thus described my invention, I claim as new and desire to secure by Letters Patent:

1. A cutting device for cutting the protective cover of shoes, boots or slippers, comprising a shaft, a sheath having a hub mounted on one end of the shaft, said sheath having a tapering end, a knife mounted in the hub of the sheath and having its cutting edge projecting beyond the tapering end of the sheath, and means for imparting movement to the knife.

55 2. A cutting device for cutting the protective cover of shoes, boots or slippers, comprising a shaft having an eccentric, a sheath having a hub mounted on the said shaft eccentric, the said sheath standing at 60 a right angle to the axis of the said shaft and having a tapering end, a knife in the said sheath and having a cutting edge pro-

jecting beyond in immediate proximity to the said tapering end of the sheath, and means for rocking the said sheath.

65

3. A cutting device for cutting the protective cover of shoes, boots or slippers, comprising a knife having a shank and a cutting edge at one end of the said shank, a sheath for the said knife and having an open tapering end through which projects the said cutting edge, means for imparting movement to the said knife, and means for cushioning the said knife relative to its sheath.

75

4. A cutting device for cutting the protective cover of shoes, boots and slippers, comprising a stand, a shaft journaled in the said stand and having an eccentric end, a sheath having a hub and mounted on the said eccentric end, the sheath having a tapering end, a knife in the said sheath and having a cutting end projecting beyond the said tapering end, and an oscillating guide mounted on the said stand and engaging the said sheath.

80

5. A cutting device for cutting the protective cover of shoes, boots and slippers, comprising a stand, a shaft journaled in the said stand and having an eccentric end, a sheath having a hub and mounted on the said eccentric end, the sheath having a tapering end, a knife in the said sheath and having a cutting end projecting beyond the said tapering end, an oscillating guide 95 mounted on the said stand and engaging the said sheath, a collar on the said knife and adapted to rest on the said hub, and a spring connecting the said knife with the said sheath to hold the said knife collar seated 100 on the said hub.

90

6. A cutting device for cutting the protective cover of shoes, boots, or slippers, comprising an oscillating hub having a sheath projecting therefrom, a knife mounted in the hub and having its cutting edge projecting beyond the end of the sheath, and means for oscillating said hub.

105

7. A cutting device for cutting the cover of shoes, boots, or slippers, comprising an oscillating hub having a sheath projecting therefrom, an adjustable spring pressed knife carried by the hub and having its lower cutting edge projecting through the sheath and its upper end projecting above 115 the hub, and means for oscillating said hub.

110

In testimony whereof I have signed my name to this specification in the presence of two subscribing witnesses.
